UNITED STATES PATENT OFFICE.

HENRY E. WOHLGEMUTH, OF DURHAM, KANSAS.

THRASHING MACHINE.

Application filed June 6, 1923. Serial No. 643,801.

To all whom it may concern:

Be it known that I, HENRY E. WOHLGEMUTH, a citizen of the United States, and a resident of Durham, in the county of Marion and State of Kansas, have invented certain new and useful Improvements in Thrashing Machines, of which the following is a specification.

This invention relates to an improvement in thrashing machines, and has for its object to provide a machine of this character wherein the grain is thoroughly threshed in an effective and efficient manner without setting up in the machine severe and destructive vibration whereby the life of the thrashing machine is considerably prolonged, and in which the parts of the machine are readily accessible for purposes of adjustment, replacement and repair.

20 A further object is to provide a thrashing machine of this character and having these advantages and in which side draft is eliminated and wherein the possibility of twine or straw tangling and massing in the arms 25 of the beater is precluded, the thrashing machine being at the same time of simple, durable construction, reliable in operation and easy and comparatively inexpensive to manufacture and operate.

30 Other objects and advantages of the invention reside in certain novel features of the construction, combination and arrangement of parts which will be hereinafter more fully described and particularly 35 pointed out in the appended claims, reference being had to the accompanying drawings forming part of this specification, and in which:

Figure 1 is a diagrammatic view, in elevation, showing the interior of the machine and the general arrangement of the parts;

Figure 2 is a fragmentary view, partly in elevation and partly in section, the casing or housing of the thrashing machine and other parts being broken away to illustrate the construction;

Figure 3 is a view similar to Figure 2, looking at the end of the machine and showing parts in end elevation;

50 Figure 4 is a fragmentary view, showing the parts in plan and parts in horizontal section and with the casing or housing and other parts being broken away for the sake of illustration;

Figure 5 is a fragmentary detail view in perspective; and

Figure 6 is a detail view similar to Figure 5, but showing the parts assembled.

Referring to the drawings wherein for the sake of illustration is shown the preferred embodiment of the invention the numeral 10 designates a conventional wheeled frame upon which a conventional housing or casing 11 is mounted to protect and contain the major operating parts of the thrashing machine. The wheeled frame 10 and the housing 11 in themselves form no part of the present invention and may be of conventional construction except as hereinafter pointed out. At the front end of the machine a transversely extending horizontal shaft 12 is arranged and is journaled in bearings 13 provided in a casting 14 bolted or otherwise suitably secured to a wheeled frame 10 and to side plates 15 having lugs 16 secured by bolts and nuts 17 to the frame. These side plates 15 are also provided with bearings 17 in which the shaft 12 is also journaled. On the central portion of the shaft 12 and consequently centrally of the thrashing machine a main pulley, designated generally at 18, is fixed and comprises two metallic sections 19 between which a section 20 of fiber is interposed, the sections 19 and 20 being held together in assembly by bolts and nuts 21. By locating the pulley 18 centrally of the machine side draft is eliminated and by constructing the pulley with a central section of fiber the frictional engagement of the belt with its pulley is enhanced so that a more effective power transmission is had.

On each side of the pulley 18 a thrashing unit, designated generally at 22 is provided. These thrashing units are of identical construction so that a common description will serve for both. Each includes a rotating disk 23 made up of two circular plates 24 and 25 assembled in face to face relation and held together by bolts and nuts 26 extending through bolt holes in the plates and through bolt holes provided in a pair of hubs 27, the members of which are arranged on opposite sides of the disk with one member engaging the plate 24 and the other member engaging the plate 25 whereby the plates 24 and 25 are firmly clamped against each other and are held against relative move-

ment. The hubs 27 are keyed or otherwise suitably fixed to the portion of the shaft located between the bearings 13 and 17. Each disk 22 carries a plurality of horizontal and laterally extending teeth 28 arranged in radial sets, as shown in Figure 2. As shown in detail in Figs. 5 and 6, each tooth 28 includes a pointed body portion 29 and a squared portion or head 30 beyond which 5 and on the opposite side of the body portion 29 a reduced and threaded stem 31 extends. When the teeth 28 are assembled with the disk 22 the head portion 30 of each tooth is received in a squared opening 32 provided therefor in the plate 24 and the stem 31 is received in a circular opening 33 provided therefor in the plate 25. In the assembly 10 the squared portions or heads 30 of the teeth are fitted in the squared openings 32 of the plate 24 and the threaded stems 31 extend through the circular openings 33 of the plate 25 and project beyond the plate and on the projecting portions of the stems 33 nuts 34 are threaded. The circular openings 33 are smaller than the squared openings 32 and are smaller than the squared portions 30 of the teeth 28 so that when the nuts 34 are threaded up against the plate 35 the teeth 28 are firmly held against end- 15 wise movement by the coaction of the heads 30 and nuts 31 with the plate 25 and these teeth are also firmly held against rotary movement by virtue of the coaction between the squared portions 30 and the walls of the 20 squared openings 32 with which they engage. Each of the rotating toothed disks 22 coact with a fixed and toothed breast 35 which takes the shape of a quadrant and which is also made up of a pair of plates, designated 25 at 36 and 37 bolted or otherwise suitably secured to each other in assembly. The plates 36 and 37 have mounted thereon a plurality of teeth 38 arranged in radial sets and associated with the plates of the breast in precisely the same manner as the teeth 28 of the disk 22 are associated with the plates 30 thereof. The plate 37 of the breast 35 has integrally formed therewith or suitably secured therewith vertically aligned apertured 40 lugs 39. In the apertures of the lugs 39 a vertical rod 40 is adjustably fitted and is secured in adjusted position by set screws 41 carried by the lugs 39 and engaging the rod 40. The rod 40 is mounted for rotary or 45 turning movement around its vertical axis in bearings 42 provided on the plate 15 with this arrangement the breast 35 may be adjusted vertically on the rod 40 so as to bring its teeth into the desired relation with respect to the teeth of the disk 22 as shown in Figure 3. Moreover the breast 35 may be swung toward or away from the disk 22 since the rod 40 on which it is mounted may be turned about its vertical axis. In order 50 to hold the breast 35 in assembly or in oper-

ative relation with respect to the disk 22 a plurality of threaded studs 43 are carried by the frame 11 and extend through openings provided therefor in the breast 35. Wing nuts 44 coact with these threaded studs and are engageable with the outer plate of the breast to hold the same in position. The portion of the frame with which the thrashing units are mounted is of semi-annular or semi-cylindrical formation as indicated at 55 70 45, so as to conform to the contour of the disks 22. It is to be understood at this point that the grain to be threshed is fed against the disks 22 above the breast 35 and is carried by the rotating disks and the 80 teeth thereof down through the space between the disks 22 and breast 35 wherein the coacting teeth of the disk and breast thoroughly and effectively thresh the grain. After passing through this space the grain 85 and straw come into the field of action of beaters 50, one such beater 50 being provided for each thrashing unit. A common shaft 51 is provided for the two beaters and is journaled for rotary movement in 90 bearings 52 provided on each side of the frame 50. The beaters 50 are of identical construction and each includes a hub 53 adjustably secured or affixed on the shaft by a set screw or other suitable means, designated at 54. Integrally formed or suitably secured to the head 53 and radially extending therefrom are a number of arms 55, each of which carries a beater blade 56. As shown in Figure 2 the beater blades each 100 traverse a portion of the disk 22 with which the beater is associated, the beater rotating in the same direction as the disk. The beater blades 54 are in the form of flat and substantially rectangular bars and the portions of such bars which extend toward the teeth of the disk 22 with which the beater is associated are provided with a plurality of inclined slots 57, the slots 57 being inclined 105 toward the rear of the machine and toward the disk 22 with which the beater is associated. These inclined slots prevent the straw and twine from tangling in the arms of the beater and at the same time provide a beater blade having a number of fingers which are effective to further the thrashing action, and to carry the straw and grain from the thrashing units onto a grate, designated generally at 60 and located below the beater 110 and forwardly of the thrashing units. The 115 grate 60 is of arcuate form so as to conform to the sweep of the beaters and portions thereof which lie below the beaters are slotted, as at 61, to provide a grate structure. Below the slotted portions of the grate 60 a deflector or baffle 62 is arranged and feeds the grain which falls through the slot 61 onto the conveyor 63. The conveyor 63 is of the endless belt type and its belt or web 64 is preferably made up of can- 120 125 130

vas and is provided at regular spaced intervals with transverse slats or bars 65 but in other respects the conveyor 63 is of conventional construction and is mounted and driven in conventional manner. The conveyor 63 feeds the grain to the usual sieve 66 which may be of any conventional construction and which has the conventional elevator (not shown) associated therewith in the usual manner. It is to be understood at this point that the features herein shown and described as constituting the present invention are adapted and are proposed for association and use with the instrumentalities ordinarily and conventionally employed on thrashing machines and well known to those skilled in the art, except of course those instrumentalities herein especially noted as replaced or omitted.

20 The straw and grain which remain therewith on the grate 60 is delivered by the beaters onto the series of spiked rollers 70. In order to insure delivery of the straw and grain remaining therewith from the beater 25 onto the rollers 70 a deflecting board or baffle 68 is provided and depends from the top of the casing behind the beater and is inclined so as to deliver the straw and grain remaining therewith which is thrown from 30 the beater onto the rollers 70. The rollers of the series 70 extend transversely of the machine and are mounted for rotation about their horizontal axes. Moreover they are provided in such manner that the series extends from a point beneath the grate 60 to 35 the rear of the machine. Each of the rollers 70 of the series has its axis or trunnions mounted for rotation in bearings 71 provided on a framework 72 and is provided with a plurality of rows of spikes 74. Preferably six such rows of spikes 74 are provided on each roller and each row of spikes extends longitudinally of this roller, the spikes of each row extending radially from 40 the roll. The spikes of adjacent rollers are staggered so that when the rollers rotate the spikes will not encounter each other.

Means is provided for rotating all of the rollers in the same direction and in a counter-clockwise direction as viewed in Figure 50 2. For this purpose one end of the shaft or axis on which each roller rotates projects beyond its bearing, and such projecting portion of each shaft has fixed thereto a pulley 75. Also below and adjacent pulleys 75 of adjacent rollers an idle pulley 76 is arranged and is adjustably mounted if found desirable and a belt 77 is trained around the pulleys 75 and in the idle pulleys 55 76 and also around a pulley 78 fixed to a shaft 79 driven by belts and pulleys 80 or other suitable gearing from the shaft 12.

As shown in Figure 1 of the drawings the series of rollers 70 overlie not only over 60 the slatted canvas conveyor 63 but also the

sieve 66 and beyond the sieve a return chute or pan 82 is provided and is disposed below the rollers and inclined toward and feeds to the sieves 66.

The straw and the grain delivered onto the rollers 70 is carried to the rear of the machine on these rollers and as it passes from one roller to the other it is subjected to the thrashing section of the spikes of the rollers which beat the straw and otherwise act 75 upon it to separate therefrom the remaining grain and chaff. This grain and chaff in the first instance falls onto the slatted conveyor 65 and as the straw is fed along the rollers beyond the slatted conveyor 65 80 the separated chaff and grain falls onto the sieves 66 and finally it falls between the rearmost rollers of the series onto the return chute 82 from whence it is delivered back to the sieves by the action of the spikes 85 74 on the lower parts of the rollers overlying the return pan 82. The straw is carried over all of the rollers and thrown from the rearmost one into the blower and stack 90 wherein it is handled in the usual manner.

The driving mechanism for the rollers 70 has been described and on referring to Figure 4 it will be seen that the beater shaft 51 is also driven from the shaft 12 by belt gearing 86. The shaft 12 serves as 95 the main drive shaft of the machine and as indicated by the fragmentary showing of the belt and pulley gearing in Figure 4 and the showing in Figure 1, it is proposed to drive the various instrumentalities of the machine from the shaft 12. With the disks 23 rotating in a vertical plane about a horizontal axis and having horizontally projecting teeth and coacting with similarly constituted breasts 35 the grain fed into the thrashing unit will be thoroughly acted upon by the coacting teeth and the thrashing action performed will be highly efficient as contrasted with the poor action of the conventional cylinder and concave wherein 100 the grain when it comes in contact with the cylinder tends to swing to the outside of the cylinder where it will not be effectively operated upon by the teeth of the cylinder 105 and concave.

An important feature of the present invention resides in the fact that the vibration which is severe and destructive in the conventional thrashing machines ordinarily employed has been practically eliminated. This then is obtained by virtue of the provision of the slatted canvas conveyor 62 in lieu of the old shaking grain pan and the employment of the series of spiked rollers and return pan neither of which shake and 115 which respectively replace the vibrating straw shakers heretofore employed and the vibrated return pan.

I claim:

1. In a thrashing machine, a disk ar- 120

125

130

4
ranged to rotate in a vertical plane about its horizontal axis and having a plurality of laterally projecting teeth and a coacting breast having laterally projecting teeth co-operable with the teeth of the disk, and a beater cooperable with the disk and including beater blades provided with a plurality of inclined notches.

5
10 2. In a thrashing machine, a rotating disk made up of two plates secured together in face to face relation, a plurality of teeth projecting beyond the plates and carried thereby, one of the plates having squared openings and the other of the plates having rounded openings, the teeth having squared portions snugly fitted in the squared openings of one plate and having rounded portions fitted in the rounded openings of the other plate and projecting beyond the same and nuts threaded on the rounded portions of the teeth and engaging the adjacent plate.

25 3. In a thrashing machine, a rotating disk having laterally projecting teeth and a cooperable breast having teeth co-operating with the teeth of the disk, said breast being mounted for swinging movement about its vertical axis, means for holding the breast in cooperative relation with respect to the disk.

30 4. In a thrasher, a rotating disk having laterally projecting teeth, a breast having cooperable teeth, said breast having vertically aligned apertured lugs, a rotating rod extending through the apertures of the lugs, means cooperable with the lugs and rods for securing the breast in vertical adjustment on said rod, and means for securing the breast in cooperative relation with respect to the disk.

35 HENRY E. WOHLGEMUTH.
